The ornamental design for a combined roll-on dispenser bottle and cap, as shown and described.

DESCRIPTION

FIG. 1 is a perspective view of a combined roll-on dispenser bottle and cap showing my new design;
FIG. 2 is a top plan view thereof;
FIG. 3 is a front elevational view thereof;
FIG. 4 is a right side elevational view thereof;
FIG. 5 is a rear elevational view thereof;
FIG. 6 is a bottom plan view thereof;
FIG. 7 is an exploded perspective view thereof;
FIG. 8 is a front elevational view of a second embodiment of the dispensing bottle and cap as in FIG. 1;
FIG. 9 is a right side elevational view FIG. 8;
FIG. 10 is a front elevational view of a third embodiment of the dispensing bottle and cap as in FIG. 1; and,
FIG. 11 is a right side elevational view of FIG. 10.
